CABLE-WAY

Frido Cruciani, 6 Via Vessella, Rome, Italy
 Continuation of application Ser. No. 729,738, Apr. 21, 1958. This application Apr. 30, 1962, Ser. No. 193,049
 Claims priority, application Italy Apr. 27, 1957
 9 Claims. (Cl. 104—115)

The present invention relates to a cable-way mounted on swinging frameworks.

This application is a continuation of application Serial No. 729,738, filed April 21, 1958.

The purpose of the present invention is to provide an improved cable-way structure capable of the most varied applications in the building art.

According to this invention the cable-way structure comprises a pair of derricks the upper ends of which are connected by a load carrying rope, an anchoring element for each end of said rope, and bracing ropes arranged cross-wise with respect to the load carrying rope.

On the load carrying rope there runs a dolly driven by a rope operated by a winch, the dolly having a lifting rope operated by a second winch. A further winch controls the swinging motion of the structure in a transverse direction with respect to the direction of the load carrying rope.

Furthermore, according to this invention, an additional and somewhat yielding anchoring system is provided for the load carrying rope, consisting in that further bracing ropes are connected to the load carrying rope at critical positions between each end of the anchorage of said load carrying rope and the next adjacent derrick. This results in a retaining force tending to oppose the transverse tilting of the derricks, so that the winch or winches designed to control the swinging motion of the structure may be of a comparatively reduced power.

This invention will be hereinafter described with reference to the attached drawings, which show by way of nonlimitative examples some preferred embodiments of the invention.

In the drawings:

FIG. 1 shows the base element of the derrick, in front elevation;

FIG. 2 is a detail view showing the connection of the tie-rods of the derrick arms;

FIG. 3 is a cross-sectional view according to plane III—III of FIG. 2;

FIG. 4 is a detail view of a top element of the derrick, in front elevation;

FIG. 5 is a side elevational view of FIG. 4;

FIGS. 6, 7 and 8 diagrammatically show the unit when mounted, in side elevation, in plan view and in front elevation, respectively;

FIGS. 9 and 10 diagrammatically show a semirigid anchorage mounting, in side elevation and in plan view, respectively;

FIGS. 11 and 12 are front elevational views of the two derricks forming the structure, the swinging movement being controlled by a single winch; and

FIG. 13 is a side view of a further type of installation, suitable for broad served zones.

With reference first to FIGS. 1 to 5, the carrying element (derrick) is essentially formed by a set of tubes 1, connected end-to-end so as to form a sturdy central column. In register with the joints are fastened cross arms 3 (FIG. 2), to the ends of which are connected tie-rods 4 connecting these arms to the adjacent joints, so as to form a strong lattice structure. The tie-rods can be tensioned by conventional tensioning devices. For more elaborate structures, additional arms are pro-

2

vided to which are connected the tie-rods which are directly connected to a base element 8 and to a top element 9. The base element, generally shown at 8 in FIG. 1, has at its lower end a rounded surface which rolls on its bearing surface when the derrick swings. Particularly, the embodiment shown in FIG. 1 shows a toothed spherical sector 10 engaging a rack 11 anchored to the ground.

The arms 3, at locations registering with the connections of the tie-rods (FIGS. 2 and 3), are provided with a projection 12 which enters a kind of chain link 13 to which are connected the eyelets 14 of the tie-rods 4.

The top element of the derrick, shown in FIGS. 4 and 5, is formed by a strong frame 9 made of metallic members on which are idling grooved pulleys 15 and 16 for the supporting and lifting ropes, while the load carrying rope runs on a saddle 18 which is arc shaped to guide the rope where its direction changes. "Rope" as used herein also means cable or line.

The saddle 18 has a flared groove 19 in order to allow a certain deflection for the rope in the transverse plane, a clamp 19' to block or grip the load carrying rope, a rocker 18' whereby said saddle rests on the frame 9, and two connecting arms 22' for the cross ropes.

The pulley 17 idles on the rocker. This type of hinged support causes the load always to be centered on the column 1.

FIGS. 6, 7 and 8 show a cable-way supported by the derricks 20, the heights of which are h_1 and h_2 while the slopes are P_1 and P_2 with respect to the vertical. The derricks 20 rest on the points 21 and the brace ropes 22 are anchored at 23, said points lying on transverse planes with respect to the load carrying rope 24 which is anchored to the ground at 25. The dolly 26 runs on the load carrying rope 24, this dolly being connected to the driving rope 27 which is operated by the winch 28 in co-operation with the idler pulleys 29 and 30.

The driving rope 27 moves in its forward run on the pulley 29 and in its return run 27' on the pulley 30. The two runs of the driving rope lead to a tensioning device comprising two pulleys suspended from the load carrying rope 24 and an intermediate pulley 31 provided with a counter weight 32, which is for the purpose of compensating the length of the rope for every position of the dolly 26. The latter is provided with the pulleys 33 about which moves the lifting rope 34, actuated by the winch 35 with the interposition of the pulley 36.

The load 37 is attached to the lifting rope 34.

It is to be noted that the direction of arrival of the rope to both the winches 28 and 35 is not affected by the inclination of the derricks owing to the presence of the pulleys 29, 30 and 36. This feature is of the utmost importance as it allows for the derricks to be swung without affecting the proper operation of the cable-way.

The function of the counterweight 38 is to maintain constant the tension of the load-carrying rope for any operating condition; this counterweight, in order to avoid heavy stresses in the rope due to an abrupt bending thereof, acts on said rope through the saddle shaped member 39. Said member is shaped as an arcuated body having on its underside a receiving groove for the load-carrying rope, said rope being fastened to member 39 to an intermediate point of the groove thereof. In this manner, when counterweight 38 pulls member 39 downwards, said member acts on the tension of load-carrying rope without causing any sharp bending thereof.

FIG. 8 shows the transverse swinging arc of the derrick 20, this arc being confined between the limit positions 20' and 20'', so that the served zone is dimensioned as shown by the dashed zone of FIG. 7.

FIGS. 9 and 10 show the brace ropes 22a fastened to

the load carrying rope at a point 41 intermediate the ground anchorage 25 and the top of the derrick. In this case obviously, the holding force on the derrick, which is determined by the rope 22a, is a function of the location of the point 41. As this holding force increases when the point 41 approaches the top of the derrick, and vanishes when the point 41 approaches the ground, an ideal intermediate point exists for a given load weight P and a given inclination angle. If locking action is carried out at this point, it will be possible to have the derrick swung by a minimum power, for instance by a winch which acts transversely thereon.

FIG. 11 shows a second measure to diminish the required power of the winch controlling the swinging movement of the derrick, by means of counterweights which although allowing inclination of the derrick, act thereon so as to render stable its erected position and ensure the equilibrium of the structure also in case of excessive inclination due to a possible misoperation of the winch. The swinging movement of the derricks may also be controlled (FIG. 12) by a single double-drum winch 42 acting on a single derrick by the rope 43 fastened to the top thereof, said rope after having passed about the anchor pulley 44 and the pulley 45 carried by the derrick, coming to re-wind about the second drum of the winch 42 in reverse winding direction. The single winch 42 although having a limited power is capable of operating the whole cable-way, in that the other derrick (FIG. 11) within certain limits is caused to become inclined by the first derrick, and the aforesaid counterweights 46 and 47, serve to stabilize the derrick for each position thereof (for instance that shown in FIG. 11 in dashed lines).

FIG. 13 shows diagrammatically another application of the cable-way, derived from that of FIG. 6, the like elements in both figures being denoted by the same reference numerals. In the structure of FIG. 13 which is used for great spans, in order to avoid excessive lowering of the lifting rope, the latter runs on movable pulley supports 48 moved by a drift rope 49 connected to one or more cable drums 50 fastened to the shaft of the winch 28 controlling the movement of the dolly. The diameter of the cable drum or drums 50 in relation to that of the drum of the winch 28 is in such a ratio that when the dolly 26 moves, the movable pulley supports are regularly moved towards or away from each other. In FIG. 13, for instance, the diameter of the cable drum 50 is equal to one half of the diameter of the drum of the winch 28. The driving rope for the movable support pulleys 48 is stabilized by the pulleys 51 as well as by the counterweight 52.

The present invention has been illustrated and described in some preferred forms of embodiment. It should however be understood that constructive variations may in practice be made within the scope of the appended claims.

Having described the invention, I claim:

1. In a cable-way, a tower-like derrick having a bottom end member supported on a base member, meshing gear teeth on the members operatively connecting the members, one of the members being curved to facilitate rocking of the derrick.

2. A tower-like derrick according to claim 1 wherein the gear teeth on one of the members are rack teeth and the gear teeth on the other member are a part of a toothed spherical sector.

3. A cable-way comprising a pair of pivotally mounted tower-like derricks, each derrick having an upper member that has a clamp, a curved saddle with a flared groove and idler pulleys for driving and lifting ropes, a load carrying rope secured by means of the clamp in the curved saddle interconnecting the derricks and having its ends anchored, and brace ropes secured to the derricks transversely relative to the plane of the load carrying rope, whereby the load carrying rope is displaceable transversely relative to its plane by pulling on the appropriate brace ropes to thereby pivot the derricks.

4. A cable-way according to claim 3 wherein the curved saddle is supported on a rocker.

5. A cable-way comprising a pair of pivotally mounted tower-like derricks, each derrick having an upper member that has a clamp, a curved saddle with a flared groove and idler pulleys for driving and lifting ropes, a load carrying rope secured by means of the clamp in the curved saddle interconnecting the derricks and having its ends anchored, and brace ropes secured to the load carrying rope transversely to the plane of the load carrying rope at points intermediate the tops of the derricks and the anchorages of the load carrying rope, whereby the load carrying rope is displaceable transversely relative to its plane by pulling on the appropriate brace ropes to thereby pivot the derricks.

6. A cable-way according to claim 5 wherein the curved saddle is supported on a rocker.

7. A cable-way comprising pivotally mounted tower-like derricks, a load carrying rope secured to the top of each of the derricks interconnecting the derricks and having its ends anchored, brace ropes secured to the derricks transversely to the plane of the load carrying rope, a dolly movably mounted on the load carrying rope, a driving rope connected to the dolly, a winch for driving the driving rope, and idler pulleys one for the forward run and one for the return run of the driving rope located between the winch and tops of the derricks, whereby the direction of arrival of the driving rope to the winch is not affected by any inclination of the derricks.

8. A cable-way comprising pivotally mounted tower-like derricks, a load carrying rope secured to the top of each of the derricks interconnecting the derricks and having its ends anchored, brace ropes secured to the derricks transversely to the plane of the load carrying rope, a dolly movably mounted on the load carrying rope, idler pulleys carried by the dolly, a lifting rope on the idler pulleys carried by the dolly, a driving rope connected to the dolly, winches for driving the lifting and the driving ropes, and idler pulleys that are adjacent the winches for guiding the lifting and the driving ropes and that are located between the winches and the tops of the derricks.

9. A cable-way comprising pivotally mounted tower-like derricks, a load carrying rope secured to the top of each of the derricks interconnecting the derricks and having its ends anchored, brace ropes secured to the derricks transversely to the plane of the load carrying ropes, and counterweights, each having a rest position and a counterpulling position, on the brace ropes, the counterweights being in their rest positions when the derricks are substantially vertical, leaning of the derricks to one side lifting the counterweights on the opposite side to their counterpulling positions to stabilize the cable-way.
